UTILITY TABLE

Arthur S. Gray, 1115 Carlyle Drive,
San Mateo, Calif. 94402

Filed May 25, 1970, Ser. No. 23,146

Term of patent 14 years

Int. Cl. D6—03

U.S. Cl. D33—14

FIG. 1 is a front elevational view of a utility table embodying my new design;

FIG. 2 is a side elevational view of the utility table;

FIG. 3 is a top plan view of the utility table; and

FIG. 4 is a bottom plan view of the utility table.

I claim:

The ornamental design for a utility table, as shown.
